[57] ABSTRACT

A lamination stacking machine is adapted to receive interchangeable heads so that the machine will accommodate a number of different size lamination plates using the same base and drive mechanism simply by lifting one head off and replacing it with a head of the desired size. The stroke of the reciprocating drive mechanism may be adjusted to the required stroke for the selected head.

LAMINATION STACKING MACHINES

BACKGROUND AND SUMMARY

This invention relates to lamination stacking machines; and more particularly, it relates to improvements in lamination stacking machines of the type disclosed in my U.S. Pat. 2,842,834 for "Methods of Applying Laminations," issued July 15, 1958, and 2,842,838 for "Apparatus for Applying Laminations," issued July 15, 1958. The disclosure of these two patents is substantially identical.

Laminations are thin metal plates which are assembled in superposed relation in an electrical coil to increase the inductance, if it is a choke, or to increase the mutual inductance of it is a transformer. Normally, the coil is wound with an open center and the core surrounds two legs of the coil, extending through the center of the coil. By far the most common practice in interleaving laminations is to insert an E-shaped lamination (having a center leg of approximately twice the width of either leg or back) into the coil with its center leg extending through the center thereof. An I-shaped plate abuts the distal ends of the legs of the E-plate to close the magnetic path about the sides of the coil. Interleaving refers to inserting alternate E-plates from different directions, and is distinguished from butt stacking wherein the E-plates are all vertically aligned.

There has been a desire on the part of persons using lamination stacking machines for building transformers and the like, to have a machine which will accommodate laminations of different sizes, as are used in making transformers of different sizes and power capacity. Machines are commercially available to stack laminations in one-eighth inch increments over a range of one-quarter inch through 2½ inches. The size of a lamination is determined by the width of the center leg of the E-plate which is approximately the width of the opening in the coil. All other dimensions of the laminations are, according to industry standards, sized or proportioned relative to this basic dimension.

There have been attempts to provide lamination stacking machines which are adjustable to accommodate different size laminations, but none have met with commercial success. One attempt at an adjustable machine employs a pair of chains which are arranged in conveyor fashion on opposite sides of a center location wherein the chains are equipped with lugs or pickers for picking laminations from the bottoms of magazines located on either side of the coil station and inserting them directly into the coil, interleaving the E-plates.

Of all proposed lamination stacking machines, to my knowledge, the machine described in my above-identified patents has been the most acceptable. However, this type of machine cannot be designed so that a single machine will accommodate different size laminations.

Having been familiar with this problem for years, I have found it difficult to adjust any portion of a lamination stacking machine for different size laminations if that portion contacts the laminations, particularly, if that portion supports the laminations while they are being pushed into assembled relation with a coil. The reason for this is that the laminations are coated with an oxide coating so as to insulate each lamination electrically from adjacent laminations. This coating is highly abrasive and is the major factor in causing wear

in lamination stacking machines. I have found that even minor adjustments to accommodate different size laminations will cause different wear patterns in machine parts which engage the laminations, and this is a primary reason for the lack of acceptance of machines that can be adjusted to accept different size laminations.

In the present invention, I have discovered that the accepted and reliable mechanism for stacking described in my above-identified patents can be used in a machine with interchangeable heads, one for each lamination size, and a common base to provide a system which can stack laminations of different sizes without the need of a separate, complete machine for each lamination size.

In a typical transformer manufacturing or production facility, not all of the machines for stacking different size laminations are in production at the same time. Those machines which are not in use are normally stored in a remote area, leaving the production area free for use with a different size machine to produce transformers of a called-for size. Thus, the entire machine not in use merely sits in storage until it is required. Another problem encountered in production facilities of this type is that when a large order is received for a single size transformer, a manufacturer would like to use as many machines as possible to fill it. It would be helpful to use a large number of machines to work on that order. However, this becomes prohibitive economically when separate machines are required and there is no assurance that large orders of the same size transformer will continue.

What is meant by a "head" is described in more detail below; however, briefly, it refers to the portion of the lamination stacking machines described in my patents which holds the laminations, picks them from their respective magazines, and pushes them into assembled relation with the coil. In other words, the "head" includes all of the portions of the mechanism which store or load the laminations, or which engage or are engaged by the laminations, or which serve as sliding or bearing surfaces for the moving laminations.

Thus, the present invention does not require widening the spacing of the magazine side plates which hold the transformers, etc., as is required in some prior attempts to provide an adjustable machine. In addition, there is the inherent advantage found in my previous machines that all parts of the machine which hold, support or transport the laminations can be fixed, this is the head portion of the machine. All of the dimensions of the lamination change as the basic size of the lamination changes, so that any machine that is based upon an adjustment in width of the magazine or transfer mechanism would also normally require adjustment of the gauging mechanism, adjustment of the picking mechanism, adjustment of the stroke of the reciprocating member, if any, etc.

With the present invention, a manufacturer, given a special order with a limited time in which to produce the transformers, may simply buy additional heads of the desired size and use his existing bases and drive mechanisms since they are of fixed sizes and adapted to accommodate heads of different sizes.

In addition, when it is desired to discontinue production of certain size transformers, production can be contained with the bases for those machines, and only the heads need be transported for storage. With the

simple interchanging structure of the present invention, the changing of heads is a very simple task.

Other features and advantages of the present invention will be apparent to persons skilled in the art from the following detailed description of a preferred embodiment accompanied by the attached drawing wherein identical reference numerals will refer to like elements in the various views.

THE DRAWING

FIG. 1 is an upper perspective view of a lamination stacking machine constructed according to the present invention;

FIG. 2 is a fragmentary perspective view of the machine of FIG. 1 with certain of the elements in exploded relation; and

FIG. 3 is a plan view of the adjustable cam for driving the cross head.

DETAILED DESCRIPTION

Referring first to FIG. 1, there is shown a lamination stacking machine incorporating the present invention including a supporting base generally designated by reference numeral 10 and adapted to rest on a bench or table top, a head generally designated 11, and a drive mechanism 12 mounted on the right side of the base 10. The base 10 serves as a frame since it is a single casting. The base 10 includes a relatively small left-hand pedestal 13, a central recess area 14, and a right pedestal 15. A connecting portion 16 extends along the bottom of the base 10 between the pedestals 13 and 15.

The head 11 has one end supported by the pedestal 13 and the other end supported by the pedestal 15, and it straddles the opening 14. The opening 14, of course, is located below the center of the head 11, and it permits an operator to have access to the bottom of a coil (one being shown and designated 17 in the drawing) for straightening leads, if needed. The coil 17 is held in the center of the head 11 at a coil station generally designated by reference numeral 18 when laminations are being inserted therein. On either side of the coil station 18 are located magazines 20 and 21. Each of the magazines is similar, and they include respectively slots for holding a stack of I-plates, 22, 23 and slots for holding stacks of E-plates 24, 25. The I-plates are located closer to the coil station 18 than are the E-plates.

The vertical side plates for the magazines 20, 21 are mounted to the tops of first and second elongated side rails 27, 28 which form the supporting frame for the elements of the head 11. The side rails 27, 28 are secured together by means of lower transverse bars, one being shown in FIG. 2 and designated 30. Still referring to FIG. 2, a pair of slots 31, 31a are machined in the side plates 27, 28 and they slidably receive a reciprocating slide, a portion of which is shown and designated 32. Located above the slides 31, 32 are machine slide surfaces 33, 34. The stacks of E-plates and I-plates rest in their associated magazines on the slide surfaces 33, 34.

Picking and pushing mechanisms as described in the above-identified patent are mounted on the top of the slide 32 so that when it is reciprocated, for example from left to right in FIG. 1, an E-plate is picked from the stack 24 and it is conveyed along the rails 33, 34 beneath the stack of I-plates 22 toward the coil 17. As the E-plate passes beneath the stack 22, an I-plate is picked from the bottom of that stack, thus forming a first pair of plates. Gauging members are employed at the front

of each of these stacks so that only a predetermined number of plates are picked, usually one. The I-plate is then superposed on the E-plate and this first pair is brought to an intermediate position, as at 37 in FIG. 1 and deposited there. The plate 32 is then reciprocated toward the left thereby gathering a similar second pair of superposed plates including an E-plate from the stack 25 and an I-plate from the stack 23 which are deposited at an intermediate location 38 in superposed relation. Thus, when the slide 32 reaches its leftmost position, it is ready to pick a third pair of plates—again from the magazine 24. At the same time, however, a pusher surface is introduced adjacent the location 37 to push the previously deposited first pair of plates in that location into assembled relation in the coil 17, the I-plate being on top engages a previously inserted E-plate to complete the surrounding of the coil, and the E-plate being on the bottom of the stack. Similarly, on the next leftward reciprocation of the slide 32, a fourth pair of plates is selected from the magazine 25 and the second pair of plates is simultaneously urged into assembled relation with the coil 17. Thus, for each reciprocation during normal operation, one pair of superposed plates is being picked from a magazine and a previously-picked pair is being moved into assembled relation in the coil, the final E-plates being inserted from alternate sides to produce an interleaved stack. The mechanism for picking and pushing the plates is completely shown and described in my previous patents identified above, the disclosure of which is incorporated herein by reference. Additional details may be obtained from those patents, if desired.

As mentioned, the present invention is directed toward a machine which will accommodate heads for different size laminations. Thus, the word "head" encompasses the structure described above and including the magazines 20, 21, the side rails 27, 28, the central core station 18, the reciprocating slide 32, and all of the mechanisms on the slide 32 for picking laminations from the magazines, delivering them to the intermediate locations 37, 38 and thence inserting them into the coil 17. Turning now to the structure which adapts the machine to accommodate different size, interchangeable heads, reference is made to FIG. 2.

The pedestal 13 includes an upper horizontal surface 40 which is co-planar with an upper horizontal surface of the pedestal 15. These two surfaces support the side rails 27, 28 of the interchangeable heads, and since these side rails are located at different spacings depending upon the size of the laminations, these upper flat surfaces just described accommodate the different size heads. A vertical pin 43 is provided in the pedestal 13 extending upwardly of the surface 40, and it is adapted to be received in a cylindrical aperture 44 in the transverse connecting bar 30. Each head has a similar connecting bar and aperture at one end thereof. The function of the pin 43 is to locate the head 11 and to prevent its moving in a longitudinal direction (that is, left to right in FIG. 1).

A slot 44 is machined in the pedestal 15, and it extends in the direction of reciprocation of the slide 32. A cross head generally designated 45 includes an elongated rectangular arm 46 which is slidably received in the slot 44 and which includes an upper surface which is co-planar with the surface 41 of pedestal 15. A transverse member 47 is welded to the top of the arm 46 at a position remote from the head 11, and it includes a

slot or way 48 which extends perpendicular to the direction of reciprocation of the arm 46. At the distal end of the arm 46, there is provided a vertical pin 49 adapted to be received in an aperture 50 in the slide 32. Thus, the interchangeable heads are replaced or mounted to the base 10 by lowering the apertures 44, 50 respectively onto the pins 43, 49. Preferably, the cross head 45 is first positioned in an extreme right-hand position and the slide 32 is pulled to its right-most position, the aperture 50 being placed over the pin 9 prior to placing the aperture 44 over the pin 43.

Located above the pedestal 15 is a rectangular cam housing 51 having a central boss 52 in which is fitted a bearing 53. Within cam housing 51 is a cam generally designated 54 which includes a vertical shaft 55 which extends through the bearing 53 and is mounted to a pulley 56. The pulley 56 is driven by means of a belt 57 which, in turn, is driven by means of a conventional electric motor. The cam 54 is thus driven in rotation. The cam 54 includes a cam plate 58 to the underside of which is removably mounted a crank pin generally designated by reference numeral 60. The underside of the cam plate 58 is seen in FIG. 3.

The crank pin 60 includes a locating pin 61 having one end received in an aperture in the cam plate 58, and the other end fitted with a bearing 62. The crank pin includes two wing members 63 and 64 which are apertured for receiving screws 66 and 67. The screws 66, 67 are threaded into corresponding internally threaded apertures in the cam plate 58. The bearing 62 is received in the slot 48 of the transverse member 47 of the cross head 45.

Referring again to FIG. 3, there are a plurality of apertures, three of which are designated respectively 70, 71 and 72 in FIG. 3 for receiving the locating pin 61 of the crank pin 60. Each of the apertures 70-72 is located at a different radial distance from the center of the cam plate 58 to adjust the stroke of the arm 46 and thereby to set the stroke of the reciprocating slide 32. Each of the apertures 70-72 is further provided with a pair of internally threaded side apertures for receiving the screws 66, 67 in attaching the crank pin 60 to the cam plate 58.

As the cam 54 is driven in angular rotation, the bearing 62 of the crank pin 60 reciprocates in the slot 48, thereby causing the arm 46 to reciprocate in a transverse direction.

As pointed out in my previous patents, the resulting motion is highly advantageous for this type of machine because the slide 32 is brought to a smooth stop at each end of a reciprocation, prior to reversing its direction.

In changing the machine to accommodate a different size head, it may or may not be necessary to change the location of the crank pin 60, depending upon the size of lamination which the new head is designed to stack. For example, I have used the four separate apertures shown in the cam plate 58 of FIG. 3 to accommodate heads ranging in size from one-quarter inch laminations up to 1 1/4 inches. Each of the apertures thus will accommodate more than one different size head, depending on the crank throw for the heads. A number of locations for the crank pin may vary with design considerations, and it is possible to use only one crank throw for all the different head sizes, although to do so would cause unnecessary travel in the smaller size laminations.

Having thus described in detail a preferred embodiment of the invention, persons skilled in the art will be able to modify certain of the structure which has been described and to substitute equivalent elements for those which have been disclosed while continuing to practice the principle of the invention, and it is therefore, intended that all such modifications and substitutions be covered as they are embraced within the spirit and scope of the appended claims.

I claim:

1. A lamination stacking machine for accommodating different size laminations comprising: a head for inserting laminations of a single size into a coil including lamination holding magazines and means for picking laminations from said magazines and inserting them into said coil including a reciprocating plate; a base adapted to support said head and including locating means engaging a stationary portion of said head for defining the position thereof while restraining said head from longitudinal motion relative to said base; and reciprocating drive mechanism providing means for releasably engaging said slide of said head to reciprocate the same, said head being removed from said base and being replaceable by a head for different size laminations.

2. The system of claim 1 wherein said drive mechanism further comprises means for selectively adjusting the throw of said slide in discrete, predetermined increments to thereby define the stroke for different size laminations.

3. The system of claim 1 wherein said reciprocating drive mechanism includes a cross head having an arm extending in the direction of reciprocation thereof and a transverse member providing a slot; a rotating cam plate having a bearing received in the slot of said cross head for reciprocating the same; one of said slide and elongated arm being provided with an aperture and the other being provided with a corresponding pin to be received therein when a head is mounted on said base.

4. The apparatus of claim 1 wherein said base includes first and second side pedestals adapted to support a head and separated by a recess located beneath a head supported by said pedestals, each of said pedestals defining a horizontal surface co-planar with the horizontal surface of the other and adapted to support interchangeable heads of different widths.

5. Apparatus for selectively inserting laminations in interleaved relation in a coil comprising a plurality of heads, each head adapted to insert laminations of a different size in said coil and including a reciprocating insertion member for inserting said laminations in said coil; a base including spaced pedestals adapted to receive and support the respective ends of pedestals of said heads and adapted to accommodate heads for different size laminations; means associated with one of said pedestals for locating one end of a head on said base while preventing longitudinal motion of said head relative to said base; a drive member reciprocably mounted in said other pedestal and adapted to releasably engage said slide of said head; and drive means for reciprocating said drive member.

6. The apparatus of claim 5 further comprising means for selectively adjusting the stroke of said drive member whereby as heads for different size laminations are mounted on said base, the stroke of the slide member of each head may be adjusted.

7. The apparatus of claim 6 wherein said adjusting mechanism comprises a rotating cam plate defining a plurality of apertures each located at a different spacing from the axis of rotation thereof; means for mounting said cam plate for rotation about a vertical axis; crank pin means removably secured to said cam plate and located by means of one of said apertures therein; a cross head including a transverse slot receiving a bearing on said crank pin and an elongated arm received in a slot on the other pedestal, said drive arm being received in said slot to prevent lateral motion thereof while permitting reciprocation of said arm in

5

10

said slot; and drive pin means including a drive pin secured to one of said elongated arm of said cross head and said insertion member, the other providing an aperture to receive said drive pin.

8. The apparatus of claim 6 wherein said locating means includes a locating pin on said one pedestal adapted to be received in a corresponding locating aperture on said head, and said drive means includes a cross head with a drive pin adapted to be received in a corresponding aperture in said insertion member.
